ABSTRACT OF THE DISCLOSURE

Fan mounted on a pulverizer shaft and separated from the pulverizer by a dividing wall having a central aperture through which the shaft extends and pulverized material passes. The fan has main blades extending axially from a rotatable disc to an annular shroud which joins the outer ends of the main blades. Flow control blades form nozzles which direct the pulverized material away from the main blades to prevent wear thereof. A sealing member extends axially from the dividing wall aperture toward the shroud to thus prevent recirculation of flow through the fan.

BACKGROUND OF THE INVENTION

In the art of reducing solid fuel to a fine, burnable consistency, it has been common practice to use the so-called "attrition" process. For that purpose, pulverizers have been built in the manner shown in the patents of Rogers No. 3,157,366 and No. 3,235,189. As demonstrated by these patents, it is common practice first to crush the fuel and then to cause the mixture of fuel and air to pass into a pulverization chamber where air currents cause the solid particles to impinge on one another and reduce them to a fine powder-like consistency. The air flow through the pulverizer is brought about by the use of a suction fan which lies in a third chamber, the third chamber having an exit opening leading to the burners of a furnace or the like. Generally speaking, these fans consist of a disc mounted on the main pulverizer rotor and have fan blades which extend axially from the disc adjacent its outer periphery. This fan operates in a chamber that is filled with comminuted fuel, some of which is fairly large in size and is later separated out in a classification apparatus and returned to the pulverizer for further comminution. This means that the fan is subject to a considerable amount of wear. In addition, a considerable amount of power is required to drive the fan, and it has been suspected that part of this power was absorbed in the recirculation of air within the fan chamber to no useful purpose. These and other difficulties experienced with the prior art devices have been obviated in a novel manner by the present invention.

It is, therefore, an outstanding object of the invention to provide a pulverizer having a fan which is subject to little wear and reduced power absorption.

Another object of this invention is the provision of a pulverizer having a fan construction in which the fuel and air mixture is directed through the fan blades in such a way as to avoid direct contact with them.

A further object of the present invention is the provision of a pulverizer having a fan section in which recirculation of air and fuel is avoided.

It is another object of the instant invention to provide a pulverizer having a fan section in which short circuiting of air from the fan periphery to the inlet has been prevented.

A still further object of the invention is the provision of a pulverizer in which maintenance costs are reduced and in which downtime necessary for replacement of fan blades has also been reduced.

2

With these and other objects in view, as will be apparent to those skilled in the art, the invention resides in the combination of parts set forth in the specification and covered by the claims appended hereto.

SUMMARY OF THE INVENTION

Generally speaking, the pulverizer consists of a housing having a shaft which extends through the housing and having bearings associated with the housing for mounting the shaft for rotation. A fan mounted in the housing includes a rotor in the form of a disc which is mounted on the shaft and which extends laterally from the shaft in a generally transverse plane. Main blades extend axially from the disc adjacent its outer periphery and include a shroud joining the outer ends of the blades. In accordance with the invention, control blades are fastened to the disc radially inwardly of the main blades, each control blade being arranged relative to a main blade to define therewith a slot for direct flow through the pulverizer away from the main blades. More specifically, each main blade is provided with a control blade, the control blade being parallel to, slightly spaced from, and slightly overlapping the main blade. The invention also includes a flange which extends radially from the edge of the aperture in the dividing wall of the fan chamber and which has a free edge located closely adjacent to the surface of the shroud to prevent recirculation of fuel and air.

BRIEF DESCRIPTION OF THE DRAWINGS

30 The character of the invention, however, may be best understood by reference to one of its structural forms, as illustrated by the accompanying drawings, in which:

FIG. 1 is a vertical sectional view of a pulverizer embodying the principles of the present invention,

35 FIG. 2 is a perspective view of the pulverizer as it appears to a person looking into the interior,

FIG. 3 is a perspective view of a control blade,

FIG. 4 is a perspective view of a filler piece, and

FIG. 5 is a perspective view of a main fan blade.

DESCRIPTION OF THE PREFERRED EMBODIMENT

Referring to FIG. 1, which best shows the general features of the invention, the pulverizer, indicated generally by the reference numeral 10, is shown as being of the general type shown and described in the patent of Rogers No. 3,235,189 which issued Feb. 15, 1966. It is provided with a pulverization chamber 11 and a fan chamber 12. In the pulverization chamber 11 resides a main rotor 13 mounted on an axial shaft 14 which, in turn, is connected to and driven by an electric motor (not shown). The shaft is mounted in bearings 20. The outer periphery of the main rotor 13 carries movable pegs 15 which lie in suitable relationship to fixed pegs 16 mounting on a dividing wall 17. This dividing wall extends between the chamber 11 and the chamber 12 and is provided with a central aperture 18 which is co-axial with the shaft 14. Mounted in the aperture 18 is a ring 19 having a tubular flange 21 whose purpose will be described more fully hereinafter.

In the fan chamber 12 is located a disc 22 which is mounted on the shaft 14 and is driven also with the shaft by the electric motor. Adjacent its outer periphery, the disc is provided with main fan blades 23 which extend axially in the direction of the dividing wall 17. Mounted on the ends of the main fan blades parallel to the disc 22 but spaced from it is a shroud 24. This shroud is simply a circular plate having an aperture 25 formed in its central portion concentric with the shaft 14. The extreme end of the flange 21 lies closely adjacent the surface of the shroud 24 at the periphery of the aperture 25.

Mounted on the disc 22 inwardly of the main fan

blades 23 are control blades 26, one control blade being associated with each main blade 23. Each control blade 26 is mounted parallel to, spaced from, and in slightly overlapping relationship to its corresponding main blade 23. Welded to the inner surface of the shroud 24 in overlapping relationship with the free end of each control blade 26 is a metal sealing strip 27.

Referring to FIG. 5, it can be seen that each of the main fan blades 23 consists of a generally rectangular main body 28. Along one side of the main body is a flange 29 by which it is bolted to the disc 22 and along the opposite edge is a flange 31 for attachment of the shroud. Referring to FIG. 3, it can be seen that each control blade 26 has a plate-like main body 32 along one edge of which extends a flange 33 by which it is bolted to the disc 22. Opposite the flange 33 the main body has a radial edge 34 which is the edge that lies closely adjacent the inner surface of the shroud 24 and which edge is in overlapping relationship to the sealing strip 27. The main body is also provided with an inclined edge 35 which, in the preferred embodiment lies at an angle of about 45° to the axis of the shaft 14. Both the main blades 23 and the control blades 26 are provided with raised ridges to promote breaking up of the boundary layer of air flowing over their surfaces.

In FIG. 4 can be seen a filler 38 which is shaped similar to the flanges 29 and 33 and extends between them to prevent there being any gap in the flanges between the control blade and the main blade. Finally, it can be seen that the wall of the fan chamber 12 is provided with an exit 36 which leads to the furnace burners and the like.

The operation of the invention will now be readily understood, in view of the above description. Most of all, the general flow of air through the pulverizer is between the movable pegs 15 and the fixed pegs 16 in the pulverizing chamber 11 radially inwardly toward the aperture 18 in the dividing wall. A mixture of air and fuel flows through this aperture around the flange 21 through the aperture 25 and the shroud 24 and starts to move radially outwardly as well as axially. As is evident in FIG. 2, the gap 37 between the control blade 26 and the main blade 23 acts as a nozzle and, with the fan rotating in the direction shown by the arrow in FIG. 2, the fuel and air between the fan blades will move radially outwardly and desirably would reach the outer periphery of the fan housing before contacting the next blade 23. Finally, the flow will enter the exit 36 and leave the fan chamber.

In prior art pulverizers, there was a tendency for the flow to also flow from the outer periphery of the main blades 23 back inwardly along the surface of the dividing wall 17 to enter the flow coming in through the aperture 18 again, thus passing through the pulverizer more than once. Since it takes horsepower on the shaft 14 to promote this type of recirculation flow, considerable losses were experienced for that reason. With the present construction, the flange 21 lying close to the outer surface of the shroud 24 near the aperture 25 prevents such recirculation. Possible bypassing of air around the outer edge 34 of the control blade 26 has been obviated by the use of the sealing strip 27.

In a commercial installation of the pulverizer of the invention, the fan efficiency has been increased about 10% by use of the present construction rather than that of the prior art as shown in the above-mentioned Rogers patent. This has reduced the pulverizer input power for the same performance level by approximately 20 kw. In other words, the power consumption on the motor driving the pulverizer has been reduced by this amount. At a cost of .6¢ per kw. for electricity and operation of the pulverizer for 8,000 hours per year, this would result in a saving of almost \$2,000 for the four pulverizers of a conventional central station steam generating unit. The maintenance of the new fan assembly was substantially less than that of the old types and there have been fewer

outages or shutting down of the pulverizer for the replacement of fan blades.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described, what is claimed as new and desired to secure by Letters Patent is:

1. A pulverizer, comprising

- (a) a housing,
- (b) a shaft extending through the housing,
- (c) bearings associated with the housing for mounting the shaft for rotation,
- (d) a fan mounted in the housing, including a rotor in the form of a disc mounted on the shaft and extending laterally from the shaft in a generally transverse plane, including main blades extending axially from the disc adjacent its outer periphery, and including a shroud joining the outer ends of the blades, and
- (e) control blades fastened to the disc radially inwardly of the main blades, each control blade being arranged relative to a main blade to define a slot to direct flow through the pulverized away from the main blades.

2. A pulverizer as recited in claim 1, wherein each main blade has a control blade associated with it, the control blade being parallel to, slightly spaced from, and slightly overlapping the main blade.

3. A pulverizer as recited in claim 1, wherein a dividing wall extends across the housing and has a central aperture through which the shaft extends, the diameter of the aperture being substantially larger than the shaft to define an air passage around the shaft, wherein a flange extends axially from the edge of the aperture and has a free edge located closely adjacent to the surface of the shroud.

4. A pulverizer as recited in claim 1, wherein the edge of the control blade which is not fastened to the disc lies closely adjacent the shroud and wherein a seal strip is mounted on the shroud and located close to the surface of the control blade to maintain the gap between the blade and the shroud to a minimum.

5. A pulverizer as recited in claim 1, wherein each main blade and its corresponding control blade are provided with flanges by which they are fastened to the discs, the flanges being of different widths so that the edges of the flanges are aligned even though the blades do not lie in the same plane, and wherein a filler is interposed between the two flanges to provide an uninterrupted radial strip fastened to the surface of the disc.

6. A pulverizer as recited in claim 3, wherein each control blade is provided with an inner edge which is inclined at an acute angle to the axis of the shaft.

7. A pulverizer, comprising

- (a) a housing,
- (b) a shaft extending through the housing,
- (c) bearings associated with the housing for mounting the shaft for rotation,
- (d) a fan mounted in the housing, including a rotor in the form of a disc mounted on the shaft and extending laterally from the shaft in a generally transverse plane and including blades extending axially from the disc adjacent its outer periphery,
- (e) a dividing wall extending across said housing defining a chamber for said fan and having a central aperture through which said shaft extends, the diameter of said aperture being substantially larger than said shaft to define an air passage around said shaft,
- (f) a shroud joining the outer ends of said blades, and
- (g) a sealing member between said dividing wall and

said shroud whereby circulation of the air from said outer periphery of said fan to said central aperture is substantially prevented.
